SKELP HEATING FURNACE

Filed Aug. 15, 1939

FIG. 2.

Inventor:

BYRANT BANNISTER,
by: John E. Jackson
His Attorney

UNITED STATES PATENT OFFICE

2,214,157

SKELP HEATING FURNACE

Bryant Bannister, Mount Lebanon, Pa., assignor
to National Tube Company, a corporation of
New Jersey

Application August 15, 1939, Serial No. 290,281

1 Claim. (Cl. 263—3)

This invention relates to a skelp heating furnace and more particularly to one which is adapted for use in the production of continuous tubing from an endless length of flat skelp which continuously travels through a furnace, the skelp being formed into a tube and its edges welded together by bending and welding rolls or other instrumentalities located at the delivery end of the furnace, from which the skelp is delivered at a welding heat.

Ordinarily, the furnace is elongated in order to permit the heating of a considerable length of skelp; and the bending and welding rolls operate to pull the skelp through the furnace. At the entry end of the furnace, the flat skelp is received for use in rolled form, and in order to deliver the skelp to the furnace in a continuous manner, it is necessary to weld the rear end of one roll of skelp to the front end of a fresh roll of skelp.

According to a prevalent mode of operation, the skelp is fed from one roll into the entry end of the furnace, and workmen unreel a length of skelp from said roll and weld the rear or trailing end thereof to the front or leading end of a fresh roll of skelp, the length of skelp uncoiled from the first roll in the meantime continuing to feed into the furnace. The fresh roll is then placed in the same position as the original roll. Subsequently, by repeating the same operation, the rear or trailing end of the skelp from the second roll is welded to the front or leading end of the skelp on the third roll.

Due to the drag of the large loop formed by the rear or trailing end of the skelp going through the furnace, which is necessary when operating at high speeds, it was, prior to the invention of my copending application, Serial No. 278,558, filed June 10, 1939, and entitled "Skelp feeding apparatus," impossible so far as I am aware to operate at speeds higher than approximately 350 feet per minute on small sized skelp, such as, for example, one-half inch. This was for the reason that the drag of the large loop caused the skelp to pull apart while in the furnace.

According to the invention of said copending application, there is provided a skelp feeding device disposed between the welding device and the entry end of the furnace, together with means permitting the formation of loops of skelp on either side of said first-named device.

It is among the objects of the present invention to overcome the feeding defects referred to hereinbefore while at the same time providing for more efficient heating of the skelp. These desiderata result in an increased production of

heated skelp, coupled with less fuel consumption and, according to the design which will be described hereinafter, is accomplished with lower initial or building costs.

The foregoing and other objects will be apparent after referring to the drawing, in which:

Figure 1 is an elevation of a skelp feeding and heating apparatus embodying the furnace of the present invention, the latter of which is shown in section;

Figure 2 is an enlarged sectional side elevation of the furnace of Figure 1; and

Figure 3 is an enlarged sectional view on the line III—III of Figure 2.

Referring more particularly to the drawing, the numeral 2 designates a continuous heating furnace which is provided with an upper longitudinal preheating chamber 3 and a lower and parallel heating chamber 4. Referring more particularly to Figure 1, it will be noted that the skelp S enters the preheating chamber 3 at the right-hand end thereof, progresses the length of the preheating chamber 3, enters the heating chamber 4 at the left-hand end thereof and exits from the right-hand end of the heating chamber 4. The strip S enters the preheating chamber 3 from the welder and looping table and leaves the heating chamber 4 for the welding and forming mill, all of which instrumentalities will be referred to more specifically hereinafter.

Referring to Figure 2, it will be noted that the heating furnace 2 provides restricted passages 5 between the upper preheating chamber 3 and the lower heating chamber 4, and suitable burner devices 6 are disposed along the heating chamber 4 at desired intervals. According to this construction, wherein the preheating chamber 3 is above the heating chamber 4, the exhaust gases from the latter are exhausted into the former and thence to recuperators through passages 9.

It will be noted that at suitable intervals along the bottom of the preheating chamber 3, and also along the bottom of the heating chamber 4, there is disposed a series of refractory skids 10, which are adapted to support the skelp S.

At the left-hand end of the heating furnace 2 and disposed intermediately of the preheating chamber 3 of the heating chamber 4, there is a pair of suitably driven pinch rolls 12, whose axes occupy a common horizontal plane. These driven pinch rolls 12 drag the strip of skelp S through the preheating chamber 3 and direct it into the heating chamber 4 from which it is drawn by the welding and forming mill. According to this construction, the pinch rolls 12 reduce the amount

of drag tension which would be required of an elongated heating furnace of the conventional variety.

Disposed somewhat adjacent the entry (or right-hand) end of the preheating chamber 3, there is suitably mounted a pair of rolls 17 and 19, respectively, each of which carries a roll of skelp. Included in the line of pass provided for the rolls of skelp 17 and 19, there is disposed a welding machine 20, while immediately adjacent the welding machine 20, is a pair of suitable driven pinch rolls 22 which are adapted to draw the skelp forwardly and permit the same to occupy a loop as at X, prior to the passage of the skelp into the heating furnace 2. At the exit (or right-hand) end of the heating chamber 4, there is disposed a tube forming machine 23, which comprises suitable instrumentalities such as bending and welding rolls, and possibly also seizing rolls (none of 20 which is shown).

While I have shown and described one specific

embodiment of the present invention, it will be seen that I do not wish to be limited exactly thereto, since various modifications may be made without departing from the scope of the invention, as defined by the following claim.

5

I claim:

A skelp heating furnace comprising, in combination, a chamber extending longitudinally of said furnace, a chamber disposed beneath and parallel to said first-named chamber, means for heating said second-named chamber, means for permitting the exhaust of the heating gases from said second-named chamber into said first-named chamber, pinch rolls adjacent said furnace for pulling skelp through said first-named chamber, said pinch rolls being constructed and arranged to reverse the direction of travel of said skelp and direct the same into said second-named chamber, and refractory skids in both of said chambers for supporting the skelp.
